WALLACE R. BURKE, Primary Examiner

J. M. GANDY, Assistant Examiner

FIG. 1 is a perspective view of an electrical terminal block for burglar alarm system showing my new design;

FIG. 2 is a top plan view thereof;

FIG. 3 is a side elevational view thereof;

FIG. 4 is an end elevational view thereof;

FIG. 5 is a bottom plan view thereof; and

FIG. 6 is a side elevational view thereof of the side opposite to that shown in FIG. 3.

I claim:

The ornamental design for an electrical terminal block for burglar alarm system, as shown.
